UNITED STATES PATENT OFFICE

RALPH E. HUTCHINSON, OF MORTON, MINNESOTA.

GARMENT-SUPPORTER.

1,213,650.

Specification of Letters Patent. Patented Jan. 23, 1917.

Application filed February 7, 1916. Serial No. 76,737.

To all whom it may concern:

Be it known that I, RALPH E. HUTCHINSON, a citizen of the United States, residing at Morton, in the county of Renville and 5 State of Minnesota, have invented new and useful Improvements in Garment-Supporters, of which the following is a specification.

This invention contemplates the provision of a garment supporter including a belt having 10 suspenders attached thereto, the supporter being designed to be arranged inside the shirt and thereby hidden from view, which adds to the appearance of the user inasmuch as the ordinary belt about the waist 15 band of the trousers is apparently the sole support for the latter.

In carrying out my invention I employ a belt adapted to be arranged inside the shirt, and constructed to be associated with both 20 the shirt and trousers as the ordinary leather belt is drawn taut about the waist band of the trousers, thereby supporting the latter and preventing the shirt from working its way out of the trousers.

Another important object of the invention resides in constructing the belt adapted to be arranged inside of the shirt from metal or like material, whereby the ordinary leather belt can be drawn as tight as necessary about 30 the waist band of the trousers without contracting the metal belt to the discomfort of the wearer.

The nature and advantages of the invention will be better understood when the following description is read in connection 35 with the accompanying drawings, the invention residing in the construction, combination and arrangement of parts as defined in the claims.

In the drawings forming part of this specification like numerals of reference indicate similar parts throughout the several views and wherein:—

Figure 1 is a perspective view of my invention showing the same applied to a figure. Fig. 2 is a perspective view of the supporter removed from the figure. Fig. 3 is an enlarged detail view of one end of the belt. Fig. 4 is a rear elevation of the same. Fig. 5 is a vertical sectional view taken on line 5—5 of Fig. 2. Fig. 6 is a perspective view of the means for fastening the adjacent ends of the belt. Fig. 7 is a vertical sectional view through the parts associated.

Before entering into a detail description of the construction herein disclosed, I de-

sire to have it understood that the same is merely illustrative of one embodiment of the invention, and that various changes may be resorted to when desired as fall within 60 the scope of what is claimed, without departing from the spirit of the invention. However as shown in this specific instance I employ a belt 5 preferably constructed from thin resilient steel, one end of the belt being 65 provided with a plurality of openings 6 for the reception of a fastening element carried by the opposite end of the belt for holding the adjacent ends of the belt operatively associated. Secured to the inner surface of the 70 belt adjacent the end carrying the fastening element are transversely disposed strips 7, the latter being split at both ends to provide the attaching lugs 8 which are bent into engagement with the upper and lower edges 75 of the belt and also the hook-like members 9 which extend over the upper and lower edges of the belt and are adapted to receive therebetween the free end of the belt as the latter is fastened about the waist of the user, 80 the hook-like members serving to maintain the opposite end of the belt in overlapping relation. The fastening element as shown in this particular instance consists of a resilient arm 10 fitted between the belt 5 and 85 one of the transverse strips 7, the free end of the arm being curved as at 11 to prevent casual separation of the fastening element from the belt. The opposite end of the arm terminates in a stud 12 normally projecting 90 through a suitable opening in the end of the belt to which the fastening element is secured, and also adapted to interchangeably engage in the openings 6 in the opposite end 95 of the belt to permit the latter to be properly adjusted about the waist of the user.

Secured to the arm 10 is a transversely extending strip 13, which latter is formed to provide bendable tongues or lugs 14 arranged in pairs at the opposite sides of the 100 strips 13 and adapted to be bent into engagement with the upper and lower longitudinal edges of the arm 10, thereby holding these parts operatively associated. The opposite ends of the strip 13 project above 105 and below the belt to provide manipulating portions adapted to be grasped to move the stud 12 out of the openings 6 when it is desired to adjust or remove the belt 5. Fixed to the belt at spaced intervals, and 110 projecting above the upper edge thereof are a plurality of loop-like elements 15 with

which is connected a pair of suspenders 16 for supporting the belt.

Secured to the exterior of the belt 5 is a plurality of substantially U-shaped clamp-
5 ing members 17 which have a length slightly in excess of the width of the belt. With the fact borne in mind that the belt 5 is placed about the waist of the wearer beneath the shirt, it will be manifest that as 10 the ordinary belt of the trousers is drawn taut, a portion of the shirt as well as the waist band of the trousers is clamped with in the U-shaped members 17. By reason of this construction the trousers are not only 15 properly supported, but the shirt is prevented from working its way out of the trousers which under ordinary conditions is a source of considerable trouble and annoy-
20 ance. The free ends of the U-shaped clamping members 17 are formed to provide a round or curved surface so as to prevent injury to the shirt as the latter is forced within the members. It is to be noted that by supporting the belt 5 by means of the 25 suspenders 16, the belt can be loosely arranged about the waist of the user, and by reason of the fact that the belt is constructed from resilient metal, the belt of the trousers may be drawn as tight as necessary to prop-
30 erly support the trousers without contracting the belt 5 to the discomfort of the wearer. It is a well known fact that when the ordinary belt is drawn taut about the waist of the user, it is injurious and re-
35 stricts the expansion of the abdomen, which objections are eliminated by the provision of the belt 5 and the manner of supporting the same.

It is believed that from the foregoing de-

scription the nature and advantages of the 40 invention will be readily apparent without requiring a more extended explanation. However while I have shown and described the preferred embodiment of the invention I desire to have it understood that I do not 45 limit myself to this construction, as various changes may be resorted to when desired as fall within the scope of the appended claims.

What is claimed is:—

1. A garment supporter comprising a belt 50 adapted to be supported about the waist of the user inside the shirt, means for adjusting the free ends of the belt, and substantially U-shaped members secured to the belt at spaced intervals and adapted to receive 55 and hold the shirt and waist band of the trousers associated therewith as the belt of the latter is drawn taut.

2. A garment supporter comprising a belt adapted to be arranged about the waist of 60 the user, one end of said belt having a plurality of openings, a resilient locking ele-
65 ment carried by the opposite end of the belt for interchangeable engagement with said openings, shoulder suspension means sup-
porting said belt, and substantially U-
shaped members secured to the belt at spaced intervals and adapted to receive and hold the shirt and waist band of the trousers 70 associated therewith as the belt of the latter is drawn taut.

In testimony whereof I affix my signature in presence of two witnesses.

RALPH E. HUTCHINSON.
